PROTECTIVE HEADGEAR

George M. Lamsa, Philadelphia, Pa.

Application January 27, 1943, Serial No. 473,733

4 Claims. (Cl. 2-4)

The present invention relates to new and improved means for protecting the face and head against insects, such as mosquitoes, flies, etc.

A primary object of the invention is the provision of an improved relationship of parts in protecting means of the said type which can be worn with a minimum of discomfort and which may effect its intended function of protecting the wearer—e. g. a soldier in tropical countries where troublesome insects abound—during the day or while the wearer is engaged in his work as well as during the night while the wearer is asleep.

A further object of the invention is to provide a relationship of parts free of metallic or similar parts which may interfere with the wearer's comfort as, for example, when he is asleep, and which shall be readily foldable into compact form, when not in use, for ready transportation and/or storage.

Further objects and advantages of the relationship of parts according to this invention will be apparent to those skilled in the art to which it pertains, from the detailed description which hereinafter follows.

The aforementioned objects and advantages are realized by the new and improved protecting means which, according to the invention, may consist essentially of a fabric or the like cap portion adapted to rest upon the wearer's head, a fabric or the like skirt portion depending from the cap portion and essentially encompassing the upper part of the wearer including his head, neck and shoulders, an inflatable netting or screen supporting frame attached to said cap and skirt portions and outlining a face opening in the latter, and netting or screening material secured to said portions and extending over said supporting frame.

A presently-preferred embodiment of the invention is shown on the accompanying sheet of drawings. It is to be understood, however, that this showing is intended to be merely illustrative, and not limitative, in character, the invention being limited only to the scope of the terms of the claims hereunto appended.

On the aforesaid sheet of drawings,

Fig. 1 is a general view of the device according to the present invention, in use; and

Fig. 2 is a plan view, with portions broken away, of the inflatable supporting member.

As shown more particularly in Fig. 1, the device may comprise a cap portion 10, made of fabric or the like and adapted to be seated on the top of the wearer's hat. The cap portion 10

may be essentially circular in shape, i. e. a sort of skull cap, and the thickness of the material thereof may be such as to assure against penetration by the sting of an insect. The material of the cap portion may be rubberized, resin-imregnated or otherwise treated, if desired, to enhance its impenetrability.

Depending from the outer periphery of the cap portion 10 is a skirt portion 11, also preferably made of insect-impenetrable textile material which, if desired, may be further treated, as above suggested, to increase the impenetrability thereof. Skirt 11 may be secured to cap 10 in any suitable and/or desirable manner, as for example by stitching and/or cementing and the like. Skirt 11 is preferably of sufficient length to extend down, as shown, over the wearer's neck and shoulders. If desired, a tie 12 may be provided around the neck portion to assure close contact at this point between the neck and skirt, so that insects may not penetrate upwardly under the latter.

The front of the skirt portion 11 is preferably cut away to provide a face opening which may essentially extend, as shown, from the wearer's forehead to his chin in the vertical direction and from cheekbone to cheekbone in the horizontal direction.

Secured to the edges of the material defining the said face opening is a supporting member which is indicated per se by reference numeral 13, Fig. 2. This supporting member may conveniently assume an essentially rectangular configuration and may comprise top and bottom elements 14 and 15 and side elements 16 and 17, as well as an intermediate transverse element 18. The top and bottom elements will rest across the wearer's forehead to chin, respectively, while the side elements will lie along the wearer's cheeks. The cross piece 18 may be disposed to bear against the bridge of the wearer's nose.

Supporting member 14 is preferably tubular in construction and is therefore capable of being inflated. For this purpose, an inflating tube 19 may be provided in the bottom element 15 or at any other suitable point on the supporting member. To inflate the supporting member, the wearer blows into the tube 19 until the desired degree of inflation has been attained. The tube 19 is then bent over at its center (see Fig. 1) and retained in place by a suitable securing member or clip 20. The inflation is effected prior to donning the protective headgear.

It is preferred to inflate the supporting member 13 to such extent as to provide an outer sup-

porting surface for gauze netting or the like 21 which is substantially removed from the wearer's face. On the other hand, it is preferred not to fully inflate the member 13 but rather to underinflate it somewhat. The reason for this is that when the wearer's cheek rests on side member 16 or 17, as when the wearer is lying or sleeping on his side, the side element will yield to the pressure of the wearer's face, and the air in such side element will be displaced to the remainder of the member 13. This yielding or flattening of the side element makes it possible to wear the protector and sleep on one's side with a minimum of discomfort.

The tubular supporting member may be made of any suitable and/or desirable material. Thus, for example, it may be made of thin rubber tubing or of tubing of rubberized or other fabric. The tubular member may conveniently be made of tubing made of silk or rayon, which may be suitably coated and/or impregnated if desired. The tube portions or elements of member 13 may be cemented or vulcanized or sewn or otherwise joined together to form the structure shown in Fig. 2.

Structure 13 may be secured to the adjacent edges of the material of the protector in any suitable manner, as by cementing, vulcanization, sewing (loops encompassing the tubular portions), etc. The protector may be made of several standard sizes to fit different head sizes.

Netting or screening material 21, which overlies the support 13 may be secured to the latter or to the fabric material 10 and/or 11 in any suitable and conventional way, as by sewing through the intermediary of an edge binding strip 23. The material 21, as is manifest, permits the wearer to see, breathe and speak therethrough, but effectively keeps insects out. To enhance the wearer's hearing capacity while wearing the device the skirt 11 may be provided with eyelet-fitted openings 22 at the parts in juxtaposition to the wearer's ears. These openings are preferably covered by netting material 21. If desired, the netting 21 covering the face opening may be provided with eye-openings covered with transparent material, such as Cellophane or the like, in conventional manner, in order to further facilitate looking through the device.

The protector is easily put on and taken off over the head. It is very light and readily foldable in compact size, due to the absence of rigid non-foldable members, such as wire or metal frame members.

The device according to the present invention is particularly useful for soldiers' use in tropical countries and in northern countries where, during certain seasons at least, insects such as mosquitoes and the like are a nuisance and a threat to the soldiers' well-being and efficiency.

It will be apparent that various changes may be made in the details of the construction, as above described, without departing from the spirit and scope of the invention as defined in the fol-

lowing claims. Thus, for example, parts 10 and 11 may be of one and the same sheet of material, instead of being formed of two separated but integrated elements. Moreover, another medium than air may be employed within the tubular frame 13.

What is claimed is:

1. Non-metallic protective head-gear comprising insect-excluding material and an inflatable hollow framework upon which said material is arranged, whereby in use said framework is interposed between said material and the wearer, said framework being collapsible at any point thereof under the influence of pressure applied at such

15 point and comprising portions adapted to extend across and in substantial contact with the wearer's forehead and chin, respectively, and side elements adapted to extend along and in substantial contact with the wearer's cheeks, respectively, said head-gear being foldable into compact form.

2. Non-metallic protective head-gear comprising insect-excluding material and an inflatable hollow framework upon which said material is arranged, whereby in use said framework is interposed between said material and the wearer, said framework being collapsible at any point thereof under the influence of pressure applied at such point and comprising portions adapted to extend

25 across and in substantial contact with the wearer's forehead and chin, respectively, and side elements adapted to extend along and in substantial contact with the wearer's cheeks, respectively and a transverse portion adapted to extend

30 between said side elements intermediate said portions and in substantial contact with the wearer's nose, said framework being collapsible at any point thereof under the influence of pressure applied at such point, whereby the head-gear may be worn while the wearer is lying or sleeping on his side or face.

3. Non-metallic protective head-gear of the character described comprising a covering for the head, neck and shoulders of the wearer, said covering being of insect-impermeable material, a netting-supporting frame attached to said covering and defining a face opening therein, said frame being collapsible at any point thereof under the influence of pressure applied at such point.

40 netting material extending over said frame, and means for securing said netting material in position, whereby said head-gear may be worn while the wearer is lying or sleeping on his side or face.

4. Non-metallic protective head-gear of the character described, which is foldable into compact portable form and comprises a netting-supporting frame, said frame being collapsible at any point thereof under the influence of pressure applied at such point, and netting material extending over and secured to said frame, whereby said head-gear may be worn while the wearer is sleeping.

GEORGE M. LAMSA.
